SMOKELESS AND ODORLESS INCINERATOR

Harry Friedberg, Cleveland, Ohio, assignor to Waste King Corporation, Los Angeles, Calif., a corporation of California

Filed Aug. 21, 1957, Ser. No. 679,334

4 Claims. (Cl. 110—18)

This invention relates to improvements in a smokeless and odorless domestic incinerator.

One of the objects of the present invention is to combine in a single domestic incinerator a number of elements and structures which have been previously known, together with some which are now as herein disclosed, so that there is the smallest possible offensive odor in the flue gases discharged into the atmosphere; smoke is eliminated; solid particles are eliminated from the flue gases; the temperatures developed in the incinerator are held so low that combustible surfaces, such as floors and walls upon which or near which the incinerator is installed are not subjected to any form of fire hazard; and any garbage load charged into the incinerator is not subjected to the processes of putrefaction but is efficiently reduced to ashes.

Another object of the present invention is to combine in a single domestic incinerator a means for slowly dehydrating a moist charge in the furnace chamber, a means for then igniting and burning the charge at a slow combustion rate so as to avoid overloading the discharge flue with an excessive amount of products of combustion, an ash trap to eliminate particulate matter larger than fifty microns, and some matter between twenty-five and fifty microns, an after burner or secondary combustion device for burning small particulate matter in the form of aerosols traveling out of the furnace chamber with the products of combustion, and a stack dilution device which aids in the slow combustion previously mentioned and which also aids in keeping the discharge flue pipe to such a temperature that it is not a fire hazard to combustible floors and walls located near the incinerator.

Other objects include the arrangement of the parts to carry out the functions mentioned above, and further objects and advantages of my invention will be set forth in the accompanying description and clearly defined in the appended claims.

In the drawings,

Fig. 1 is a vertical sectional view taken centrally through an embodiment of my invention and generally along the line 1—1 of Fig. 2;

Fig. 2 is a fragmental perspective view of a portion of the device of Fig. 1 with certain parts broken away and the ash trap moved out of its operative position in order to more clearly show the construction of the parts; while

Figs. 3, 4 and 5 are respectively a front elevational view, a top plan view, and a side elevational view of the secondary combustion device seen at the upper right hand portion of Figs. 1 and 2.

It has become evident for some time that awakened interest in air pollution problems would inevitably dictate that refuse incinerators be so designed that they would not contribute to the air pollution problem. I believe I am the first to combine in a single incinerator all of the features herein disclosed and so interrelated that almost any combination of domestic refuse can be consumed in the incinerator with practically no air pollution

whatsoever. Each part of my device contributes to the efficiency and functioning of the whole and each element contributes to the unitary result.

Referring now to Figs. 1 and 2, a furnace chamber 10 is formed by means of a front wall 11, side walls 12, a rear wall 13 and a bottom wall 14. The front wall includes an offset portion 11a for the accommodation of an ash drawer 15, which may be removed for dumping through a suitable opening in the casing utilizing the handle 16. Practically, the furnace and the ash pit are all a single chamber merely being separated by a grate 17 which may be reciprocated by means of handle 18 which is welded to a bracket 19 which is in turn welded to the grate. A false rear wall 20 is provided 15 for the furnace chamber 10, this wall being the front wall of an ash trap to be described later. There is a partial top wall 21 covering the space between the side walls 12 and extending substantially the distance between the walls 13 and 20 already described. Other 20 than this, the furnace chamber is open at the top as indicated at 22 for the introduction of material to be burned.

The ash trap comprises a front wall 20 mentioned previously on the side toward the furnace chamber, two 25 generally parallel side walls 23 rigid with the front wall and extending rigidly therefrom and resting snugly inside of the side walls 12 of the furnace chamber sheets. The trap also has a bottom wall 24 which slopes from the front downwardly toward the rear and stops short of the 30 rear wall 13 of the furnace chamber section so as to allow material collected on the said bottom wall 24 to work toward the rear and fall downwardly into the ash trap 15 deflected by a baffle member 25 secured to the rear wall 13.

35 Within the ash trap, impingement baffle plates are provided to catch the larger particles which come over with the products of combustion, to dissipate the kinetic energy of such particles, and thus permit them to fall substantially vertically downward in the ash trap. In 40 the present instance, the ash trap is provided with a roof plate 26 rigidly connected to the front plate 20 and to the side plates 23 and sloping slightly downwardly toward the rear. A V-shape baffle plate 27 extending substantially vertical has upper tongues 27a less than the full 45 width of the legs of the V-shape baffle extending upwardly through suitable openings in the roof plate 26, and tongues 27b at the lower end of a similar character extending through suitable openings in the bottom plate 24. When the plates 24 and 26 are rigidly assembled in the ash 50 trap as shown in the drawings, the V-shape baffle 27 is firmly held in the position shown. Other baffle plates 28, two being shown on each side of the baffle 27, are arranged generally parallel to the arms of the baffle 27 and each baffle plate spaced slightly rearwardly from the 55 plate immediately forward of it, and overlapping at that point, so as to provide flow openings 29 extending the full height of the baffles between the two adjacent baffles 28 on each side and between the baffle 28 and baffle 27 on each side of the latter. The plates 28 are held in 60 place like the baffle 27 by means of upper tongues 28a extending through plate 26 and lower tongues 28b extending through plate 24.

65 Preferably, the ash trap is removably mounted in the furnace. In the drawings, this is accomplished by providing two U-shaped seats 30, one secured to each of the side walls 12 and adapted to receive the lower edge of plate 20 of the ash trap. This provides a simple pivotal mounting so that the ash trap may be swung from the operative position of Fig. 1 to an inspection position of 70 Fig. 2, or thereafter the ash trap could be lifted out of place. It will be noted that most of the weight of the ash trap lies toward the right of the pivot seats 30 as in Fig. 1.

and therefore this device will normally return from the tilted position of Fig. 2 to the operative position of Fig. 1. Two metal screws are shown at 31 which engage through suitable openings 32 in an upstanding flange attached to the plate 20 and engage in other suitable openings 33 in a flange connected with the top plate 21 to secure the ash trap in its operative position. These are necessary when shipping the device but otherwise would not be called for.

The ash trap above described substantially seals off the right hand side of the furnace chamber 10 as viewed in Fig. 1 save for an opening through which the products of combustion pass outwardly to the flue. This opening is preferably covered with a coarse screen of hardware cloth or heavier rods as indicated at 34.

The flue pipe 35 is connected to the flue collar 36 in the customary manner and is at the same level as the opening covered by the screen 34. At this same level, a secondary combustion device 37 is provided. This device preferably constructed of a suitable ceramic refractory material so as to provide a maze of material adapted to stand the high temperatures encountered there and to give intimate contact between highly heated surfaces and the unconsumed particles in the gases leaving the furnace chamber 10, together with a supply of secondary air or oxygen so that all of these small particles are consumed in the secondary combustion device and do not pass out through the flue pipe 35. The particular device 37 is clearly shown in Figs. 3, 4 and 5. It consists of a vertical back plate 38, a horizontal top plate 39, a centrally located vertically extending partition plate 40, and a plurality of arcuate plates 41 which pass through suitable openings in the partition plate 40. The arrangement is such that the arcuate members 41 act as baffles so that the products of combustion cannot pass straight through the secondary combustion device but instead are diverted and come into contact with highly heated surfaces. The secondary combustion device is held in place by two bolts 43 which attach the same to the plate 13.

Means is provided to slowly dry out any moisture in the material charged into the furnace chamber 10. Means is also provided for heating the secondary combustion device 37 to a temperature preferably 1200 degrees Fahrenheit or higher. My present invention combines these two functions by the use of a combined burner shield and duct 44, preferably of cast iron or the like, having a generally horizontal duct-like portion 44a connected by suitable bolts to the front wall 11 of the furnace chamber. There is a registering opening through the front wall 11 which registers with the hollow opening through the burner shield which is otherwise generally cylindrical in section and generally imperforate. The burner shield has a rearward generally vertically extending portion 44b which extends upwardly and terminates just below the secondary combustion device 37. The parts are so arranged, as clearly seen in Fig. 1, that much of the weight of the burner shield is held on the baffle member 25. Preferably, but not necessarily, the horizontal portion 44a of the burner shield is generally ovoid in section as clearly seen in Fig. 2 with the arcuate end of smaller radius upwardly so that material does not readily lie on the top of the burner shield. Preferably also, but not necessarily so, the vertically extending portion 44b is gradually changed to a rectangular section and flared outwardly as it extends upwardly so that the terminal upper end is generally rectangular in form with its longer dimension generally parallel to the plate 38 of the secondary combustion device.

Means is provided for heating the burner shield portion 44a substantially continuously to a temperature below 400 degrees Fahrenheit, the preferred value being between 250 and 290 degrees Fahrenheit. This is the ideal temperature for this portion of the burner shield, in order to enable it to radiate that portion of the infra-red spectrum which has the greatest ability to penetrate the charge in the furnace. In so doing, dehydration without combus-

tion of the charge is readily accomplished. Such dehydration, as is well known, stops bacterial action by the removal of moisture and tends to eliminate the production of alcohols which otherwise would subsequently be oxidized to aldehydes.

The aldehydes are major corporates producing offensive odors and have been blamed for the irritating nature of the "smog" which is a plague in some of our major cities. The temperature of the horizontal burner shield portion 44a is such, due to the constantly applied heat as to never rise high enough to ignite the charge in the furnace chamber 10, or to cause the same to smolder. In the present embodiment, this means for heating the horizontal portion 44a to the dehydration temperature is the small burner 45 which I have called

15 the main burner because it operates all of the time. This burner is designed for a fluid fuel such as gas or oil. The form here shown burns gas continuously and consumes 800 to 1000 B.t.u. per hour of natural gas. This is somewhat less than one cubic foot of gas per hour.

20 Means is provided for heating the secondary combustion device 37 preferably to a temperature of 1200 degrees Fahrenheit or higher so as to provide incandescent surfaces which will cause the combustion of finely divided particles otherwise passing out of the furnace chamber

25 10 to the flue pipe 35. This could be a separate means, but I prefer to combine it with the aforesaid burner shield and duct and have, therefore, bent the same upwardly to provide the vertical duct-like portion 44b to carry combustion gases to a point directly beneath the

30 secondary combustion device. At the same time, it is desirable periodically to ignite the dehydrated charge in the furnace chamber 10. I thus accomplish both of these purposes by providing a burner 46 of greater heating capacity than the burner 45 so that periodically the burner

35 46 may be ignited so as to raise the burner shield portion 44a to a temperature high enough to ignite the charge in the furnace chamber while the products of combustion of the burner 46 travel up the burner shield portion 44b to heat up the secondary combustion device to the desired

40 temperature. To accomplish this double purpose, the burner 46 which I call the after burner, is provided with a capacity of 20,000 to 30,000 B.t.u. per hour using natural gas. It will thus be noted that the fuel capacity of the burner 46 is between 20 and 40 times greater than that of the burner 45.

45 This after burner 46 has many functions. When energized, it heats the horizontal burner shield portion 44a to a temperature in excess of 800 degrees Fahrenheit which is more than ample to ignite a charge in the furnace chamber 10 which is in contact with the burner shield. Approximately 25 percent of the energy released by the after burner is used up in igniting the charge.

50 When burning, the after burner aids in establishing and maintaining a proper and satisfactory draft in the venting system connected with the flue pipe 35. At an input of 20,000 B.t.u. per hour, the after burner sends up the chimney approximately 200 cubic feet of flue gases and excess air per hour. This is a considerable amount and imparts a useful velocity to the flue gases. The other function of the after burner has been mentioned, namely,

55 to superheat the products of combustion of a burning or smoldering charge and bring the ceramic maze of the device 37 to a temperature at which catalysis can function.

60 It is believed unnecessary to describe the air and fuel supply to the burners 45 and 46 which are of a standard construction and supplied with the usual safety devices.

65 The after burner 46 is actuated by a combination timer and safety control which is known and sold under the trademark Incinitol. The burner 46 is ignited by the constant burning main burner 45 when the control member turns on the fuel to burner 46. All of the burner equipment and control devices are housed in the shield 70 47 which is attached to the front wall of the casing.

75 Extra oxygen is needed for the combustion of the products passing through the secondary combustion device 37. This could be provided in several ways but as here shown,

atmospheric air is introduced as follows. Referring to the lower left hand portion of Fig. 1, there is provided an opening 48 which allows air to enter, under stack draft pull, from the atmosphere to the space between the furnace chamber walls and the surrounding casing. At this particular point, a bottom plate 49 provides the casing member nearest the floor and a space is provided between this and plate 14. The entering air then passes in the direction of the arrows of Fig. 1 between these two plates and then upwardly on the outside of plate 13 and between this plate and the rear wall of the surrounding casing. There is an opening 50 through plate 13 at a suitable point along side the burner shield portion 44b. Here, the cold air enters the ash trap and travels upwardly along side the hot burner shield 44b (when burner 46 is operating) and thus the heated air passes over the ceramic maze of the device 37 during that time when the device 37 is being heated to a very high temperature by burner 46. Thus, the gases from the furnace charge mix with the preheated combustion air entering through the opening 50 and, because of the elevated temperature in the device 37, the extra oxygen and the contact with the ceramic maze surfaces, the gases are caused to burn in a secondary combustion which burns the hydrocarbons to carbon dioxide and steam. It is interesting to note that the flue gases leaving the secondary combustion device 37 are much hotter than when they entered it.

As mentioned previously, I use a barometric draft dilution device in order to hold the combustion in the furnace chamber 10 at a rate where the products of combustion can be handled and give a smokeless and odorless incinerator. This device indicated generally at 51 in Fig. 1 is like that shown and claimed in my copending application Serial No. 525,955, filed August 2, 1955, for "Barometric Stack Dilution Device." The present application covers the novel combination of this stack dilution device with the secondary combustion device 37.

The stack dilution device includes a closed passageway 52 of rectangular section which communicates at the upper end with the flue pipe 35 at a very short distance outside the vent collar 36 as clearly seen in Fig. 1. At its lower end, the passageway 52 communicates with a box 53 of larger cross section than the passageway 52. This box is completely closed save for a slotted opening 54 at the bottom side thereof. The arrangement is such that air entering from the atmosphere through opening 54 must make three right angle bends before it passes out the flue 35. The passageways 52 and 53 are of such a size as to require a stack draft in excess of .025 inch to .030 inch (water gauge) to overcome the resistance of the passageways 52 and 53. Experience has taught that at draft pressures of .030 or less, combustion in the incinerator chamber 10 is sufficiently slow so that it is completed within the combustion chamber and practically none takes place in the flue pipe. Since the average chimney, under primed conditions, rarely has a draft in excess of .010 inch of water gauge, there is no problem of excessive draft in the furnace chamber 10 except at such time as the after burner 46 is energized so that the large volume of products of combustion pass out the flue 35 from the burner shield 44 as previously described. The operation of the stack dilution device 51 is such that when the draft at the flue collar 36 passes .015 inch water gauge, a very small amount of air enters at the opening 54. At such time as the draft pressure in the flue 35 increases, when the higher rates of combustion prevail after burner 46 is lit, more and more air enters at the opening 54 so that the draft pressure at the flue collar 36 is held below .025 or .030. At these higher rates of combustion, the cold air flowing through the passages 53 and 52 enters the flue pipes 35, cooling the flue pipe and its gases over the flue length entirely, reducing the flue pipe and gas temperature to a safe level. An additional arrangement which holds the top of the flue pipe 35 to a safe temperature just outside the incinerator is the introduction of a false top 35a

in the flue pipe exactly like that shown at 35 in my above mentioned copending application, which serves the double purpose of protecting the top of the flue pipe from direct contact with the hot gases passing through the main portion of the flue pipe and at the same time provides a space between the partition member 35a and the top of the flue pipe so that air entering in the direction of the broken line arrows of Fig. 1 may travel directly through this passageway and cool the top of the flue pipe at that point.

- 5 10 In the operation of my incinerator a compromise is necessary in that I limit the amount of air introduced into the combustion chamber 10. This is necessary in order to control the rate of combustion at a desired level. If sufficient air for complete combustion were permitted 15 to enter the burning zone, combustion would be too rapid and the major portion of the burning gases would be found in the venting system, giving rise to red hot flue pipes and conditions hazardous to combustible material in close proximity to the flue pipe. I, therefore, 20 restrict the amount of air delivered to the combustion chamber to slow down combustion, to obviate burning in the venting system and to keep flue temperatures within reasonable limits. This is accomplished by the stack dilution device 51. Too rapid combustion releases more 25 flue gases than the average venting system can handle. In devices not constructed according to my teachings, this evidence of too large a volume of flue gases is evidenced by outward leakage around the charging door, seams, etc. A properly operating incinerator has a neutral pressure zone some inches below the charging door. This is a 30 fairly definitely marked plane, below which the flue gases are expanding and leak out of every possible opening, and above this neutral pressure zone air is sucked into the combustion chamber. This zone dictates the position of 35 the vent collar 56. The charging door is above this zone and air is sucked into the combustion chamber through the door seat. This charging door is indicated at 55 closing and opening just above the open top 22 of the furnace chamber 10. The charging door is pivoted to the casing 40 at 56 and is provided with a handle 57 for manual operation. Also, if desired, an ear 58 may be extended rearwardly rigid with the door 55 and there attached to a link 59 which extends forwardly and downwardly to a point 60 where it is pivotally attached to a foot lever 61 which 45 in turn is pivotally mounted on the frame or casing at 62.

Because I limit the rate of combustion in the chamber 10, for the reasons mentioned above, there are occasions when the amount of air entering the combustion chamber results in unburned gases reaching the flue system. This 50 condition is corrected by utilizing the secondary combustion device 37. The net result of this combination is that I burn the combustibles in the chamber 10 at a controlled rate but nevertheless insure that no unburned material, or substantially none, passes out the flue pipe 35.

55 The function of the mounting of the ash trap on the hinge brackets 30 is to facilitate access to the interior of the ash trap and access to the secondary combustion device 37, by tilting the ash trap forwardly on its bottom pivots as illustrated in Fig. 2. It will be noted that there is 60 a recess 24a cut in the bottom plate 24 of the ash trap to fit around the upstanding portion 44b of the burner shield. Also, there is a recess 20a cut into the bottom edge of the plate 20 of the ash trap so as to fit over the burner shield portion 44a and this recess is large enough to permit the 65 tilting action shown in Fig. 2.

The operation of my incinerator should now be apparent. Material to be consumed is placed in the furnace chamber 10 by opening the charging door 55. The burner 45 preferably operates continuously and maintains a temperature below 400 degrees Fahrenheit in the burner shield portion 44a which slowly dehydrates any moisture in the charge. At periodic times, the after burner 46 is turned on which increases the temperature of the burner shield portion 44a to the ignition point of the charge and 75

the hot gases from burner 46 travel up the burner shield portion 44b heating the secondary combustion device 37 to incandescence. At the same time, additional air entering through the opening 50 travels along the hot burner shield portion 44b so that it is preheated before reaching the secondary combustion device to aid in additional combustion of unburned products there. All this time, the stack dilution device 51 is limiting the amount of combustion air drawn into the furnace chamber 10 as previously described. The air for combustion enters through the opening 48 near the lower left hand corner of the drawing in Fig. 1 and passes between plates 14 and 49 as previously described. There are other openings as indicated in plate 14 and 63, and also alongside the side plates 12, where air may pass upwardly through a passageway between front wall 11 and the front wall of the casing, this passageway being indicated at 64. Other air passes upwardly through the passageway between rear plate 13 and the rear wall 65 of the surrounding casing. This passageway is marked 66. The air passing up passageways 64 and 66 and like passageways between the side walls 12 and the generally parallel walls of the casing at those points, all passes through the open top 22 of the furnace chamber as shown by the curved arrows in Fig. 1. Thus, substantially all of the combustion air for the charge in the furnace 10 enters from the top. The amount of this air is restricted by the stack dilution device 51 previously described. As the products of combustion pass out the opening in the upper portion of wall 20 of the ash trap and through the screen 34, the heavier particles impinge upon the baffles 27 and 28 and drop downwardly into the ash trap. Since the bulk of the air flow is across the top of the ash trap, the lower portion thereof is very quiescent and the particles settle to the bottom of the ash trap and later fall into the ash pit. The rest of the products of combustion pass through the secondary combustion device 37 where the smaller particles are completely consumed utilizing the excess oxygen supplied by the air entering through the opening 50 as previously described. All of the products then pass out the flue pipe 35 which is further cooled by additional air drawn through the passageways 52 and 53. At the same time, the top of the flue pipe at the exit from the incinerator is cooled by the air passing between the plates 35a and the top of the flue pipe. Thus, all of the factors which I have described combine together to give a substantially completely smokeless and odorless incinerator.

What is claimed is:

1. In a domestic incinerator, walls forming a furnace chamber open at the top and having front and rear walls and two opposed side walls and a bottom wall, a casing surrounding said chamber on all sides and spaced outwardly therefrom, there being an opening in the upper end of said casing for the introduction of the charge to be consumed, there being registering openings through said furnace chamber rear wall and casing rear wall near the top of said rear wall and a hollow flue connection extending through and engaging all sides of said registering openings, a hollow combined burner shield and duct extending from said front chamber wall horizontally through a lower portion of said chamber to a point near said rear chamber wall and then extending upwardly to a point slightly below the level of said flue connection, an ash trap comprising a front partition wall extending approximately the entire distance across said chamber between said opposed side walls from the top thereof down to a level below said burner shield and duct, said trap having walls extending rearwardly from said front partition wall, said partition wall being imperforate save for a through opening horizontally opposite said flue connection, baffle means supported in said trap permitting only non-linear gaseous flow through said baffle means, a secondary combustion device positioned at said flue connection near the top of said upwardly extending burner shield and duct, and providing a maze of ceramic material

able to withstand a temperature of at least 1200 degrees Fahrenheit through which products of combustion must pass from said furnace chamber to said flue connection, there being a small opening through said rear furnace wall adjacent said upwardly extending portion of said burner shield and duct and communicating with the atmosphere for supplying combustion air to said secondary combustion device.

2. An incinerator comprising an outer casing, an inner casing within the outer casing, partitioning means in the inner casing forming on one side thereof a combustion chamber and on the other side thereof a secondary combustion zone and a fly-ash trapping zone, an exhaust flue communicating with the upper portion of said chamber and adapted to be connected to a draft source, a secondary combustion catalyzer disposed in said zone adjacent the junction between said flue and said chamber and on the chamber side thereof, partition means near the exhaust side of said combustion chamber compelling products of combustion to leave said chamber through an opening substantially horizontally opposite said flue and catalyzer, baffle means between said opening and said catalyzer preventing straight line flow of products of combustion therethrough, a combined burner shield and duct mounted in the lower portion of said outer casing extending horizontally partially therethrough and then bending upwardly and terminating at a zone adjacent said catalyzer on the chamber side of said partitioning means, means providing a supplemental source of oxygen to said catalyzer, a main and after burner fluid fuel burner means in said outer casing and communicating with said burner shield and duct at a point spaced from the upward bend of the same, said main burner means having a capacity for heating said burner shield and duct to a temperature under 400 degrees Fahrenheit, said after burner means having a capacity for heating said burner shield and duct to a temperature over 800 degrees Fahrenheit, and a stack dilution device providing communication between the atmosphere and said flue approximately at the junction between said flue and said chamber holding the draft from said source under approximately 0.030 inch water gauge whereby an induced flow of air from atmosphere through said device is thus operative to cool said flue during high rates of combustion in said chamber.
3. An incinerator comprising an outer casing, an inner casing within the outer casing, partitioning means in the inner casing forming on one side thereof a combustion chamber and on the other side thereof a secondary combustion zone and a fly-ash trapping zone, an exhaust flue communicating with the upper portion of said chamber and adapted to be connected to a draft source, a secondary combustion catalyzer disposed in said zone adjacent the junction between said flue and said chamber and on the chamber side thereof, partition means near the exhaust side of said combustion chamber compelling products of combustion to leave said chamber through an opening substantially horizontally opposite said flue and catalyzer, baffle means between said opening and said catalyzer preventing straight line flow of products of combustion therethrough, a combined burner shield and duct mounted in the lower portion of said outer casing extending horizontally partially therethrough, means providing a supplemental source of oxygen to said catalyzer, burner means for heating said combined shield and duct only to a temperature under 400 degrees Fahrenheit, burner means for heating said catalyzer to approximately 1200 degrees Fahrenheit, means for igniting a charge in said chamber, and a stack dilution device providing communication between the atmosphere and said flue approximately at the junction between said flue and said chamber holding the draft from said source under approximately 0.030 inch water gauge whereby an induced flow of air from atmosphere through said device is thus operative to cool said flue during high rates of combustion in said chamber.

4. The combination of claim 2 wherein said means providing a supplemental source of oxygen to said catalyst comprises a passageway communicating at one end with atmosphere and extending adjacently along said upwardly bent portion of said burner shield and duct and communicating on its opposite end with said chamber.
